JOHN P. WEIS, OF NYACK, NEW YORK, ASSIGNOR TO METROPOLITAN SEWING MACHINE CORP., OF NYACK, NEW YORK, A CORPORATION OF DELAWARE

UPSIDE DOWN SEWING MACHINE

Application filed July 15, 1927. Serial No. 205,869.

This invention relates to sewing machines, the object of the invention being to provide an improved convertible upside down sewing machine particularly adapted for hemming and inserting circular elastics in the waist band and bottoms of knickerbocker bloomers and similar articles, although it may be used for a variety of purposes, such as hemming the arm holes and neck openings and bottoms of bathing suits and underwear. It is also well adapted for various other purposes such as general stitching operations where the formation and character of the seams are of such a nature that they can be more readily made by reversing the work as the seams are formed to have the folded edges always come on top in plain view of the operator, rather than have such folded edges come underneath out of sight, whereby the seams and stitches can be more accurately made with greater speed of production and the work handled with greater facility.

In stitching articles where the chain stitch is objectionable on the right side of the garment, it is difficult to arrange the machine for the convenient handling and guiding of the work to the stitching mechanism so that the chain stitches will appear on the wrong instead of the right side of the garment. Therefore, there has always been a demand for a chain stitch sewing machine that would reverse the usual conditions and make the chain stitch on top instead of on the bottom of the work. Various attempts have been made to provide a machine in which the needle will operate underneath the cloth plate while the looper and feed mechanism operates above the cloth plate. None of the machines of which I am aware, that have attempted to do this however are applicable for general sewing operations, for they are more or less unhandy and cumbersome to work with, for the reason that the reversal of these mechanisms requires a total reconstruction of the essential features of the machine, and the cost of manufacture of such a machine is a serious disadvantage since in view of the reorganization required the machine becomes a special one.

I have found that by making certain important changes and without the necessity

of redesigning or reconstructing the regular Metropolitan cylinder sewing machine this machine is particularly well adapted for reversal to have the looper and feed and its operating mechanisms above the work, with the needle, presser foot and their operating mechanisms below the work. The regular Metropolitan cylinder sewing machine is furnished with an automatic stop motion for stopping the needle in its uppermost position. In the present improvement this mechanism is omitted. The needle is positioned by turning the handwheel for the handling of the work. The removal of this stop motion mechanism from the machine does away with a great many parts and simplifies the construction of the machine and makes it more readily adapted to the character of work herein described.

When this machine is reversed, the bottom of the presser foot becomes a substitute for the top surface of the usual throat plate or cloth plate or work rest of the usual sewing machine, and as the needle threads must be protected from the work, while the presser and needle bars must likewise be guarded against injury to the operator and damage to the materials being handled, some material changes in construction and arrangement are essential. As the bottom of the presser foot becomes the work support, it likewise becomes the supporting surface for attachments, guides, etc., which are used to form the hems and guide the edges of the work to the stitching position and since the presser foot has the usual up and down yielding action to cooperate with the feed, if the attachments or guides are secured to it they also operate up and down with the presser foot. However, a work rest cloth plate can be provided by attaching it to the machine frame so as to be stationary, and have the presser foot operate through an opening therein similar to the way the usual feed operates up and down through the opening in a cloth or throat plate. In the present instance, however, I employ a hemmer and guide attached directly to the bottom of the foot, which is carried with it.

In the present improvement it is necessary to provide an opening in the bottom wall of the machine frame trunk casting to receive

the small reservoir and oil straining screen that is normally used at the top of the machine when the machine is right side up. The oil pump was removed from the reservoir 5 in the trunk of the machine and the lead pipe conducting the oil from the pump to the top reservoir and strainer was also removed. A new back cover plate indicated by 97 is provided having integral therewith an oil reservoir 95, which fits up over the opening in which the top reservoir and screen is normally located when the machine is right side up. When the machine is upside-down, this opening is below all the working parts of 10 the machine and by placing the oil reservoir 95 directly under this opening and having the joint between the reservoir and the sewing machine frame sealed with a gasket to prevent leakage, the oil may be circulated from the reservoir 95 by the pump up through a lead pipe to that portion of the machine attached to the angle bracket, delivering the oil to a reservoir where it passes through the strainer and then finds its way to all the working parts 15 to properly lubricate them. In order to accomplish this many of the internal oil leads had to be changed for instance, the oil grooves in the bearings are shifted from what was normally the top of the working parts to the 20 bottom thereof, so that when the machine is upside down, these oil grooves will come on the top to properly feed the oil to the bearings. By having the cover plate 97 and the main reservoir cast together and carrying the oil pump as a unit, it is a simple matter to 25 attach or detach this lubricating means to the regular machine, the only machine operation necessary being the making of an opening in the base of the machine trunk casting for the 30 small reservoir and strainer.

To conveniently and properly control the threads to the looper and needle, the thread handling mechanism is changed somewhat to facilitate threading and also protect the 35 threads during the operation of the machine. Certain guards are provided and the thread leads arranged in an accessible manner for ease of threading with the machine in the upside down position.

40 The means for operating the presser foot also required some change in that the actuation of the presser foot when the machine is in its upside-down position is just the reverse of its normal working position. I make use 45 of the arrangement of parts shown and represented by the elements 39 to 44 inclusive. The chain 41, for instance attached to one end of the reverse lever 39 pulls down to lift the presser foot when the machine is in the upside down position, whereas when it is used in its right side up position, this reverse lever is forced upward, at the end where the chain is attached by a push rod which also operated 50 the starting and stopping mechanism of the regular machine.

The presser foot for use on an upside down machine is arranged to afford a means for supporting attachments, guides, etc., and to be of sufficient size to conveniently act as a work plate. The arrangement of the presser foot may vary according to the character of work the machine is intended to do. In each instance, however, it is desirable to have a suitable opening through this foot in front of the needle line in order that the operator may see through this opening to simplify the threading of the needle, for without such an opening, the eye of the needle cannot be seen without getting down and looking up underneath, which is very difficult and an 55 awkward thing to do.

For some stitching operations a small ordinary size presser foot could be used in conjunction with a stationary work rest carried by some part of the machine frame casting, as for instance supported by the needle bar bearing. Such work rest could be provided with an opening through which an ordinary presser foot could operate in a similar manner to which a feed dog operates through the 60 openings of a throat plate. Such arrangement would be desired for any kind of work that would be of considerable heft or bulk, for the reason that there is a limit to the weight of a presser foot and its mechanism 65 due to the speed at which these machines must operate. It is therefore desirable to always have the presser feet and the other moving parts connected therewith to be as light as possible consistent with the proper 70 strength to stand the strain.

To properly support the machine upside down in such position that the working elevation or plane of the work will be identical with the usual plane of handling the work 75 when the machine is operated right side up, I have provided a suitable angle bracket.

For this purpose and to avoid the necessity of re-designing the machine frame, I make use of a Z shaped angle bracket. It will be 80 understood that the shape of the supporting bracket may be varied to suit different kinds and characters of work to arrive at the best and most convenient working position to facilitate the handling of the work.

Among the advantages of this improved upside down machine is first of all an important economic one, since there is very little change if any required in the tooling equipment for the manufacture of the machine, the special parts required being reduced to a minimum since the same machine is convertible for stitching right side up or bottom side up by changing a few parts. With the machine upside down for some work there is a decided advantage to the operator in that she can see the formation of the stitches by the looper and needle, the action of the feed of the work and the formation of the hem and the guidance of the hem directly 90

up to the needle, which is not the case when the machine is used right side up. Another advantage is that the machine when used upside down, virtually becomes a post machine. The position of the arm in which the needle bar and presser bar operate form a post and provide considerable space and clearance for the work, thus enabling the handling of either bulky work or on the other hand, stitching around very small tubular articles. Moreover, the suspension from the work table of the machine provides a clear drop for the work all around the stitching mechanism, which facilitates the handling of the goods and enables a larger production. The cylinder type of machine is particularly well adapted for operation in the upside down position, because the cylinder bed does not obstruct the view of the operator as the stitching proceeds. Moreover, it provides clear space and adds to the freedom of handling the work and an inspection of the work as the seams are completed.

One of the objects also present of the invention is the provision of an improved means for securing an elastic strip in the hem of a garment between the folded portion of the hem and the body of the garment or work so as to permit its ready removal without the necessity of forming a buttonhole for this purpose.

A further object is the provision of means for diverting the folded or hemmed edge of a garment thereby to form an unstitched portion or pocket to permit the ready withdrawal and insertion of an elastic strip.

In the drawings Fig. 1 is a perspective view of the machine in its working position supported by the angle supporting bracket on the work table, the electric motor drive for operating the machine being also shown; Fig. 2 is an enlarged detail top view of the looper operating parts, thread take-up, presser foot, hem folder guide and edge controlling mechanism for shifting the hem of the work, looking in the direction of the arrow, Fig. 1; Fig. 3 is a side view showing the machine in its operating position with the angle supporting bracket secured to the work table, and illustrates the casing for the oil pump and reservoir and the treadles for operating the transmitter and sewing machine, also the foot treadle for shifting the presser foot; Fig. 4 is a detail view of the presser foot with the parts attached thereto in section; Fig. 5 is a perspective detail view of the hem formation and the inserting of the elastic, and the means for diverting the edge out of the path of the needle; Fig. 6 is a view representing the hem of a garment with a circular endless elastic strip stitched therein; Fig. 7 is a detail view of a piece of goods hemmed with the elastic inserted under the fold of the hem; Fig. 8

is a detail view of the circular elastic with its ends joined before it is placed in position so that the goods can be folded over the same.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, since the invention is capable of other embodiments, and that the phraseology which I employ is for the purpose of description and not of limitation.

The work table or bench has secured to its under side an electric motor 2, or any well-known form of power clutch transmitter, so that pressure on the foot treadle 3, secured to the floor as at 4, will cause movement of the rod 5, or chain 6, see Fig. 1, connected with the starting lever 7 of the electric motor to operate the clutch 8 and drive the belt 9 when required. A detailed description of the power transmitter is unnecessary, since no claim is made thereto, as any of the power clutches now in use may be employed.

Attached to the top of the table is an angle bracket 10 of any suitable form to support the sewing machine. In the present instance, however, the top portion 11, to which the base 12 of the sewing machine is attached by screws 13, is provided with a rectangular opening 14 for the purpose of access to the lubricating system of the machine, and through this opening may be reached the strainer or filter and the top reservoir, which distributes the oil to the various working parts of the machine. A detailed description of the lubricating system is deemed unnecessary, since it forms no part of the claims of this invention and is clearly shown in my patents for cylinder sewing machines. Attached to the angle bracket is a thread stand rod 15, carrying a supply of thread 16. The threads lead directly to tubes 17 carried by the sewing machine. One tube carries the looper thread and the other tube carries the needle thread. A suitable opening is provided in the wall of the angle bracket, for the passage of these tubes.

The sewing machine comprises a base 12, having a trunk 18, in which the major working parts operate, and a cylinder 19 secured in the boss 20 of the trunk 18. The cylinder carries a looper shaft, feed bar and their usual operating parts. Carried by the cylinder is the throat plate 21. Projecting from the trunk 18 is an arm 22 and this arm carries a rock shaft 23 for operating the usual needle bar mechanism and its needle 24. The needle and presser bars operate in the portion 25 of the arm 22, which form bearings 26 for the needle and presser bars. Attached to this bearing 26 by screws 27 is a sheet metal

guard 28, see Figs. 1 and 3, of suitable form to cover up the working parts and protect the operator from injury. When the machine is operating in the usual upright or normal position, the presser bar and needle bar operating parts are usually exposed, they not being covered by a guard. But it becomes very important to cover up these parts when the machine is operated upside down, not only to protect the operator, but also to prevent the goods from catching on to the moving parts and also prevent the oil from damaging the goods. A swinging guard 29 having side walls 30 and 31, guards the needle and needle bar in its movement. This guard is made so as to swing out of position for convenience in threading the needle and may be attached to the presser bar 32 in a suitable way so that it may be operated conveniently and at the same time give proper protection. Attached to the presser bar 32 is the shank 33 of a presser foot 34, which may be rigidly connected to the presser foot. This presser foot is large enough to cover the entire feeding surface of the feed and also to carry attachments, hammers, guides, etc.

Since the needle is below the presser foot, I have found it desirable to provide the presser foot with a suitable opening 35, through which the operator can get a clear view of the needle eye, so that the needle may be threaded as readily as if it were above this foot. By looking down through this opening, 35, the eye of the needle is in view and by swinging out the guard 29, the needle threading becomes a very simple matter, whereas without this opening the operator would have to stoop down and look up underneath in order to see the needle eye to thread the needle. Therefore, it will be understood that this opening in the presser foot for the purpose of threading the needle, is of considerable importance for without it, the threading of the needle would be quite difficult. The presser foot has its forward end bent downward as at 36, (see Figs. 1 and 3) forming an incline over which the work may travel.

The presser foot is held against the feed by the usual spring 37, and a lever 38 pivoted to the machine arm as at 45 enables the presser foot to be shifted to and from the throat plate and feed. A reverse lever 39 is pivoted at 40 and has a chain 41 attached to its rear end which is connected to a foot treadle 42 to enable the operator to shift the presser foot by pressing on the treadle. To carry the weight of the treadle, and prevent rattle and noise while the machine is operating, I interpose a spring 43 connected to the chain 41 and to the side of the machine as at 44.

The presser foot has secured to it a hem folder 46 provided with a shank or bracket 47, secured to the presser foot by screws 48 and adjustably mounted so that its guiding

end 49 projects close up to the stitching position to the right of and directly opposite the needle.

The hem folder shown comprises an arm 50 attached to the bracket 47 and to the scroll portion 51, which has a base plate 52 extending out from a portion of the opening 35 of the presser foot. This scroll portion 51 is attached to and forms part of the guide 49 as indicated at 53. This portion of the hemmer is positioned directly in front of the front edge of the throat plate and in line with the needle so as to control the margin of stitching relative to the folded edge of the hem. Carried by the arm 50 of the hem folder is a swinging portion of the hemmer indicated at 54. This swinging part is arranged to swing out when the stitched hem feeds around in a circle to its starting point of the work as it approaches the horn 55 of the folder. The goods are wrapped around this horn as the hem is being made and the circular band of elastic is guided directly underneath this horn so that the fold of the hem of the goods is merely led over the band of elastic and not folded around it to encase the elastic within the inner fold of the hem, that is to say, the goods are merely led over the elastic as shown in Figs. 5 and 7. The hem folder has a pivoted swing support 56, which may be of any suitable construction, as for instance, a stud screw and a spiral spring having one end attached to the arm 50 and the other end attached to the stud screw, a suitable adjustable thimble overhanging the stud screw so that the tension on the spring may be regulated. There are many ways in which the swing out portion of the folder may be mounted for convenient operation to permit the removal of the hem from the folder after it is finished.

At the forward end of the presser foot is attached a spring 57, the other end of which is attached to a lever 58, shiftable by hand on its pivotal stud screw 59, tapped into the presser foot at the rear end. The presser foot is provided with a stop pin 60, projecting up through a slot 61 in the lever 58, which limits the movement of the lever. Attached to the lever and also provided with a slot is an adjusting piece 62, secured by a screw 63 tapped into the lever 58. This piece has secured to it by a screw 64, a wire edge controller having a loop 65 surrounding the screw and adjustable relatively thereto. This wire reaches over and is formed with a bent up portion 66, (see Fig. 4) having a downwardly projecting end 67, to engage the folded edge 68 of the hemmed goods and divert it or pull it out of the path of the needle when desired, as is clearly illustrated in Fig. 5 by dotted and full line positions. The purpose of this diverter is to shift the hemmed edge of the goods out of the path of the needle so as to leave an unstitched portion for the with-

drawal from and insertion of the elastic into the hem and so provide for the quick and easy renewal of the elastic. The completed hem, representing a rayon or silk bloomer or the like, is shown in Fig. 6, in which the body portion of the garment is indicated at 69 and the hem at 70, while the folded over edge which is stitched down is indicated at 68, and the unstitched diverted open hem portion is represented by 71. The hemmed under raw edge 72, lies over and upon the elastic strip 73. This is an important difference from the usual hemming, where elastics are inserted in the hem or pocket, for the elastic usually is laid in on top of the folded edge portion 72. I find it important to avoid this whenever it is desired to have the hem constructed so as to permit the ready renewal of the elastic strip, for when the elastic is placed as shown, it is always exposed through the opening 71 and can be readily withdrawn whereas if the elastic were placed between the folded portion 72, and the top portion of the hem 74, it would be difficult to unfold the raw edge, which is inside the hem in order to get at the elastic strip for its removal. The chain stitch portion of the hem is indicated by 75 on the inside of the garment, while the needle thread portion of the stitch is indicated at 76 at the outside of the garment. The elastic strip is joined together by zig-zag or hand stitching at 77, see Fig. 8.

The formation of the chain stitch may comprise one or two threads. I have shown a thread carrying looper for making the two thread chain stitch, although a looper can be attached to make the single thread stitch.

The looper is indicated at 78 and is attached to the usual looper carrier 79, which is secured by a collar 80 to the looper shaft 81. A looper thread take up 82 and looper thread take-up guide 83 are provided for controlling the looper thread. The conduct and handling of the looper and needle threads is identical with that shown in the Metropolitan sewing machine above referred to and therefore needs no further description.

The feed prongs 84 of the feed dog, see Fig. 2 are carried by the usual feed bar and project through the openings in the throat plate, the forward portion 85 of which is provided with an elongated slot 86, through which projects the end 67 of the diverter so as to come directly in contact with the folded edge of the hem. The bent up portion 66 of the diverter permits the presser foot to be shifted or moved downward for placing and removing the work from between the presser foot and throat plate. The diverter is flexible enough to yield when it comes in contact with the portion 87 of the throat plate so as to provide ample clearance between the end 67 and the surface of the presser foot for the removal of the work.

To guard and cover up the looper mechanism I provide the usual end cap 88, see Fig. 3. The belt 9 operated by the transmitter operates the combined hand and belt wheel 89, for operating the sewing machine. It will be observed that this belt wheel 89 and the power-driven mechanism extend from adjacent to the inner end of the underhung arm and substantially at right angles thereto. A belt guard 90, see Fig. 1 is attached to the angle bracket as at 91 to protect the operator. The belt wheel 92 over which the belt 9 rides is carried by the shaft 93 of the oil pump. This oil pump is contained in the casing 94, which is provided with a reservoir 95 and an oil gauge 96, see Fig. 3. The oil pump reservoir and back cover 97 comprise a unit readily attached and detached to convert a standard machine for upside down use.

The rectangular opening 14 in the angle bracket affords means for introducing the oil into the machine and also provides space for the usual oil gauge, which indicates when the lubricating mechanism is operating properly.

For hemming and inserting elastics in the hem, the operation of the machine is as follows:

The operator presses downward on the foot treadle 42 and operates the levers 39 and 38 to lower the presser foot, leaving space between it and the working surface of the throat plate and feed. The goods and the elastic loop are then passed into the hem folder 46, so as to fold the raw edge of the goods, up, over, and under. When the initial fold in the goods has been made and drawn into stitching position, the pressure on the foot treadle is released and the work is clamped between the presser foot, throat plate and feed surfaces. The treadle 3 is then depressed, giving movement to the rod 5 and the clutch lever 7 so as to put the transmitter in operation, which gives movement to the belt 9 and the hand wheel 89, thereby starting the stitching and feeding operations. The hemmed portion of the garment is stitched and the elastic loop is tensioned and guided into the folder by hand, or in some instances it may be tensioned by a small tension carried in front of the folder to stretch and narrow the elastic as the stitching proceeds. It is to be noted, however, that in hemming and inserting circular elastics, it is not essential to always stretch the elastic, for the reason that the elastic loop is made to a predetermined size with respect to the garment into which it is to be stitched before the stitching operation is commenced, therefore, the finished size of the garment is established by and under the control of the circular elastic strip and as the gathers of the garment are free to slide along the elastic, it is not important that the tension be applied to the elastic uniformly,

as it is guided into position at the time the hem is formed. The stitching may proceed until it is desired to divert the edge to make the opening 71, when the lever 58 is shifted to divert the hemmed edge out of the path of the needle while a few stitches are made, and then the lever is released and the parts returned to their initial position and the stitching proceeds until the starting point arrives close to the horn 55 of the folder, at which time the swinging portion 54 of the folder is swung to the dotted line position Fig. 2, so that the ending up of the stitching operation overlaps the beginning of the stitching of the hem for about $\frac{1}{2}$ inch or more, then the presser foot is again shifted and the work removed. To facilitate this, the tensions may be released so that the threads will draw through the tensions freely.

The hemming of garments and providing an endless loop of elastic for the hemmed portion has been common practice for a long time, either by free hand guiding or by the use of some form of a guide or hem folder. The renewal of worn out elastics by introducing them into the hemmed portion of the garments with a small instrument, such as a tape needle, hair pin, or safety pin, is also well-known and commonly used. To facilitate the renewal of elastics some of the hems of the garments have been provided with a button hole. The button hole must be made in the hemmed portion of the garment before the hem is formed. It is a difficult matter to always locate the button hole with respect to the raw edge of the hem so that when the hem is formed it will always come in the correct position on the inside portion of the hemmed fold of the garment, for if a little too much goods is folded into the hem, the stitches securing the hem may cross through the center of the button hole. On the other hand, if not enough goods is turned in the button hole may come on the top edge of the garment. For these reasons the button hole has been unsatisfactory. Moreover, it requires a button hole machine and a separate operation of taking the garments to and from the button hole machine for the making of the button hole. With the present improvement for diverting the edge out of the path of the stitches, leaving the opening 71, the expense of making the button hole is eliminated, the opening comes always at a definite position relative to the formation of the hem and leaves an opening of sufficient size for ready access to the elastic for its renewal. The shifting of the diverter takes place while the machine is in operation and therefore it does not in any way retard production. The garment is completely finished on the one machine so far as the hemming and elastic inserting are concerned, which offers considerable advantage

to the manufacturer with the added advantage to the wearer of the garment when it becomes necessary to renew the elastic.

I believe that I am the first to provide a diverter for diverting the hemmed edge of an elastic hem to avoid the use of a button hole and thereby provide a better means by which the elastics of hemmed garments can be renewed. This important feature, together with the added advantage of folding the raw edge over the top of the elastic rather than around the elastic is of advantage to the manufacturer of the garments for it effects a substantial saving. On the other hand, it is an advantage to the wearer of the garment, for it simplifies the task of renewing the elastics when necessary.

While I have provided a special form of hemmer for conveniently hemming the work wrong side up and diverting the edge of the hem from the stitch line directly in view of the operator, the invention is not limited thereto, for it will be readily understood that the diverter can be eliminated especially on some kinds of work and the opening 71 can be provided by starting the stitching at one side of the opening shown and ending it at the other side, leaving an open unstitched space of sufficient size to permit access to the elastic in the hem.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A sewing machine having a trunk, a needle carrying arm located adjacent to the base of the trunk, a presser bar and foot carried thereby, an overhanging cylinder carried adjacent to the top of the trunk, feed and cooperating stitch mechanism carried by the cylinder, a work attachment carried at the end of the cylinder and above the needle for forming a hem for the insertion of an elastic, and means for diverting a part of the hem thereby to expose the elastic and permit its ready removal.

2. In an upside down sewing machine, the combination of a trunk having an opening at its bottom, a supporting bracket secured to the top thereof for supporting it on its work table, an overhanging cylinder carried by the trunk, an underhung arm below the cylinder, a needle and its operating mechanism carried by the arm, a feed and cooperating stitch mechanism carried by the cylinder above the arm and its needle, an oil reservoir secured adjacent to said opening

and means for forcing the oil therefrom to lubricate the working parts.

3. A sewing machine having a trunk, a needle carrying arm located adjacent to the base of the trunk, a presser bar and foot carried thereby, an overhanging cylinder carried adjacent to the stop of the trunk, feed and cooperating stitch mechanism carried by the cylinder, means for forming a hem and for inserting an elastic strip between the hem and the body of the garment, and means for pulling a part of the hem from the stitch line thereby to leave a portion of this hem unstitched to permit the ready removal of the elastic strip.

4. In an upside down sewing machine, the combination of a trunk, an overhanging cylinder, an underhung arm below the cylinder, a needle and its operating mechanism carried by the arm, a presser foot mechanism carried by said arm, a feed and cooperating stitch mechanism carried by the cylinder above the arm and its needle, a folder carried by the presser foot for forming a hem for the insertion of an elastic, and means for diverting a part of the hem thereby to expose the elastic.

5. In an upside down sewing machine, the combination of a trunk, an overhanging cylinder, an underhung arm below the cylinder, a needle and its operating mechanism carried by the arm, a presser foot mechanism carried by said arm, a feed and cooperating stitch mechanism carried by the cylinder above the arm and its needle, a folder carried by the presser foot for forming a hem for the insertion of an elastic, means for diverting a part of the hem thereby to expose the elastic, and a lever for operating said diverting means.

6. A sewing machine having a trunk, a needle carrying arm located adjacent to the base of the trunk, a presser bar and foot carried thereby, an overhanging cylinder carried adjacent to the top of the trunk, feed and cooperating stitch mechanism carried by the cylinder, means for forming a hem for the insertion of an elastic at such hemmed portion, and means for diverting a portion of the hem from the stitch line thereby to permit the ready removal of the elastic.

7. In an upside down sewing machine, the combination of a trunk having an opening at its bottom, an inclined supporting bracket secured to the top thereof for supporting it on its work table, an overhanging cylinder carried by the trunk, an underhung arm below the cylinder, a needle and its operating mechanism carried by the arm, a feed and cooperating stitch mechanism carried by the cylinder above the arm and its needle, an oil reservoir secured adjacent to said opening, and means for forcing the oil therefrom to lubricate the working parts.

8. In an upside down sewing machine, the

combination of a trunk having an opening at its bottom, a supporting bracket secured to the top thereof for supporting it on its work table, said supporting bracket having an opening in the top thereof to permit access to the lubricating system, an overhanging cylinder carried by the trunk, an underhung arm below the cylinder, a needle and its operating mechanism carried by the arm, a feed and co-operating stitch mechanism carried by the cylinder above the arm and its needle, an oil reservoir secured adjacent to said opening, and means for forcing the oil therefrom to lubricate the working parts.

9. In an upside down sewing machine, the combination of a trunk having an opening at its bottom, an inclined supporting bracket secured to the top thereof for supporting it on its work table and provided with a substantially rectangular opening in the top thereof to permit access to the lubricating system, an overhanging cylinder carried by the trunk, an underhung arm below the cylinder, a needle and its operating mechanism carried by the arm, a feed and co-operating stitch mechanism carried by the cylinder above the arm and its needle, an oil reservoir secured adjacent to said opening, and means for forcing the oil therefrom to lubricate the working parts.

10. In an upside down sewing machine, the combination of a trunk having an opening at its bottom, a supporting bracket secured to the top thereof for supporting it on its work table, an overhanging cylinder carried by the trunk, an underhung arm below the cylinder, a needle and its operating mechanism carried by the arm, a feed and co-operating stitch mechanism carried by the cylinder above the arm and its needle, an oil reservoir secured adjacent to said opening and means for forcing the oil therefrom to lubricate the working parts, and a back cover plate for the trunk, said plate carrying said oil reservoir.

11. In an upside down sewing machine, the combination of a trunk having an opening at its bottom, a supporting bracket secured to the top thereof for supporting it on its work table, an overhanging cylinder carried by the trunk, an underhung arm below the cylinder, a needle and its operating mechanism carried by the arm, a feed and co-operating stitch mechanism carried by the cylinder above the arm and its needle, an oil reservoir secured adjacent to said opening and means for forcing the oil therefrom to lubricate the working parts, and a back cover plate for the trunk, said plate having integral therewith said oil reservoir.

12. A sewing machine having a trunk, a needle-carrying arm located adjacent to the base of the trunk, a presser bar and foot carried thereby, an overhanging cylinder carried adjacent to the top of the trunk, feed

and co-operating stitch mechanism carried by the cylinder, a work attachment carried at the end of the cylinder and above the needle for forming a hem for the insertion of an elastic, and wire-formed means for diverting a part of the hem thereby to expose the elastic and permit its ready removal.

13. A sewing machine having a trunk, a needle-carrying arm located adjacent to the base of the trunk, a presser bar and foot carried thereby, an overhanging cylinder carried adjacent to the top of the trunk, feed and co-operating stitch mechanism carried by the cylinder, a work attachment carried at the end of the cylinder and above the needle for forming a hem for the insertion of an elastic, and a single, hook-shaped, wire-formed means for diverting a part of the hem thereby to expose the elastic and permit its ready removal, said diverter being located over the folded edges of the hem.

14. A sewing machine having a trunk, a needle-carrying arm located adjacent to the base of the trunk, a presser bar and foot carried thereby, an overhanging cylinder carried adjacent to the top of the trunk, feed and co-operating stitch mechanism carried by the cylinder, a guard carried by the needle arm, a hem folder located in position for folding a hem in the body of the goods, for the reception of an elastic and means for pulling a part of the hem away from the stitch line thereof to expose the elastic.

Signed at Nyack, county of Rockland,
35 State of New York, this 13th day of July,
1927.

JOHN P. WEIS.
